MACHINE FOR ATTACHING HANDLE
HANGERS

Eugene D. Hanset, Portland, Oreg.

Application January 19, 1937, Serial No. 121,273

3 Claims. (Cl. 140—93)

This invention relates to improvements in machines for attaching hangers on soft or hard-wood handles such as are used on brooms, dust-mops, push brooms, mop sticks and the like. The type of hanger used with the present invention is shown and described in my co-pending application, Serial No. 100,659, filed September 14, 1936.

The principal object of the present invention is the provision of a machine by means of which the hangers may be quickly, conveniently and accurately shaped and permanently attached to handles, in such a manner that both legs of the hanger will be of identical shape and of equal length. By methods heretofore used to attach hangers to handles no provision was made to prevent the prongs or inwardly turned ends of the hangers from becoming deflected or distorted by the grain of the wood in the handle, with the result that the hangers when finally driven into engagement with the handle would assume various irregular shapes. But with my machine I provide a means for firmly embracing both legs of the hanger to maintain their shape throughout the compressing operation and for causing the bending of the hanger to take place at its center and in no other place.

Other objects and advantages will appear as the invention is more fully hereinafter described in the following specification, illustrated in the accompanying drawings and finally pointed out in the appended claims.

In the drawings:

Figure 1 is a perspective view of my new machine.

Figure 2 is a detail plan view of a feeding mechanism for the hangers.

Figure 3 is an enlarged sectional view taken on the line 3—3 of Figure 2.

Figure 4 is an enlarged front elevation of a handle centralizing mechanism and a hanger compressing mechanism.

Figure 5 is a top plan view of Figure 4.

Figure 6 is an enlarged perspective view showing the formation of the ends of the centralizing and compressing blades.

Figure 7 is an enlarged sectional view through a handle showing the compressing blades at the completion of their operation and the hanger compressed into engagement with the handle.

Figure 8 is a fragmentary elevation of the end of a handle showing the hanger applied thereto in finished form.

Referring now more particularly to the drawings—

The main body of the machine consists of a head 1 supported by any suitable number of legs 2. A channelway 3 is formed centrally of the head and extends inwardly from the front face thereof, and is adapted to receive the end of a broom handle to which a hanger is to be attached. In alignment with the channelway and extending rearwardly therefrom is a hanger feeding mechanism consisting of an arm 4 shaped in section as shown in Figure 3 and 10 adapted to slidably support a plurality of hangers 5 which are preferably glued together for reasons to be hereinafter pointed out. A follower block 6 is slidably mounted on the arm 4 behind the hangers and is adapted to maintain 15 forward pressure on the hangers by means of cables 7 whose ends are attached to one end of a spring 8. The opposite end of the spring is attached as at 9 to a treadle arm 10. The cables 7 are attached to the rear end of the follower 20 block 6 and extend over pulleys 11 thence through apertures 12 formed in the head of the machine. By this arrangement the tension on the cables causes a forward pressure on the hangers 5 and advancement thereof each time the treadle arm 25 is depressed.

The centralizing and compressing elements arranged on the front face of the head comprise two sets of blades 13 and 14 slidably mounted in suitable brackets 15 which are secured to the 30 front face of the machine. The centralizing blades 13 have their inner ends notched or V-shaped, as at 16, as best illustrated in Figures 4 and 6. The opposite or outer ends of these blades are turned at right angles to themselves 35 as at 17 to receive one end of coil springs 18. The opposite ends of the springs are attached to pins 19 which extend through elongated slots 20 into engagement with the plates 14 and the bifurcated ends 21 of a pair of arms 22 which 40 are pivoted as at 23 to the front face of the machine. The lower ends of the arms 22 are turned inwardly as shown in Figure 1 and slidably engage with angularly disposed slots 24 45 formed in a cam plate 25 which is slidably attached to the front face of the machine by means of studs 26 which are secured to the front face of the machine and which extend through an elongated slot 27 formed in the cam plate. The 50 lower end of the cam is interconnected, by a pair of links 28, with the treadle arm 10 as shown. As the treadle arm is depressed, the cam plate is moved downwardly and causes a spreading of the lower ends of the arms 22 with a re- 55

sultant inward movement of the upper ends thereof.

In Figure 5 it will be seen that the ends of the centralizing blades 13, when at rest, are in advance of the compressing blades with respect to the handle being dealt with. Thus when the treadle arm is depressed, the centralizing blades will first come in contact with the broom handle 30 and arrange it centrally of the channelway 3. 10 The spring connection between the pins 19 and the ends 17 of the blades 13 allows the arms 22 and the pins 19, working in the slots 20, to further advance the compressing blades 14 to grip the ends of the foremost hanger and to compress them into engagement with the handle. 15

The ends of the compressing members 14 are grooved and shaped as shown in Figure 5 to correspond in shape with the downwardly and inwardly turned ends of the hanger as shown in Figures 3 and 7. This particular shape of the 20 ends of the compressing blades allows the hangers to be compressed into the handle without becoming twisted or distorted by the grain of the wood in the handle, and also causes the bending 25 of the hanger to take place at its apex. Thus, the parallel portions of the legs of the hanger are finally positioned in parallel relation to the sides of the handle.

The end of the hanger supporting arm 4 disposed within the channelway is provided with a 30 projection 31 to convey the foremost hanger forward into reach of the compressing blades 14 and away from the sides of the arm 4 so that the hanger can be compressed. All of the hangers on 35 the arm are glued or otherwise removably held together, not only for convenience in handling but also to stabilize the foremost hanger as it clears the arm 4 in its advancement out over the projection 31 into position to be gripped by the 40 compressing blades.

While I have shown a particular form of embodiment of my invention, I am aware that many

minor changes therein will readily suggest themselves to others skilled in the art without departing from the spirit and scope of my invention. Having thus described the invention what I claim as new and desire to protect by Letters Patent, is: 5

1. A machine for applying hangers to handles comprising a head, a horizontal channelway in the head, centralizing blades movable transversely of the channelway and adapted to centralize a handle with respect thereto, compression blades 10 movable toward each other transversely of the channelway and adapted to compress a hanger into the handle, and means for simultaneously moving all of said blades into centralizing and compressing positions. 15

2. A machine for applying hangers to handles comprising a head, a channelway in the head, a hanger-supporting arm having one of its ends disposed within the channelway and adapted to slidably support a plurality of hangers for advancement into the channelway, a follower block slidably mounted upon the arm and adapted to apply forward pressure to the hangers, centralizing means movable transversely of the channelway and adapted to centralize a handle with respect thereto, compression blades movable toward each other transversely of the channelway and adapted to compress a hanger into the handle, and means for simultaneously moving all of said blades into centralizing and compressing positions. 20

3. A machine for applying hangers to handles comprising a head, a horizontal channelway in the head, centralizing blades movable transversely of the channelway and adapted to centralize a handle with respect thereto, compression blades 35 movable toward each other transversely of the channelway and adapted to compress a hanger into the handle, and means for progressively moving the centralizing blades and then the compression blades into their operative positions. 40
